United States Patent Office

Des. 178,657
Patented Sept. 4, 1956

178,657

BUILDING

Melvin M. Greene, Port Chester, N. Y., assignor to Milk Maid Ice Cream Co., Inc., Rochester, N. Y., a corporation of New York

Application November 1, 1955, Serial No. 38,678

Term of patent 14 years

(Cl. D13—1)

Fig. 1

Fig. 2

Fig. 3

The dominant features of my design reside in the portions shown in full lines.

I claim:

The ornamental design for a building, as shown and described.
